RAILWAY TRUCK CONSTRUCTION

Oscar J. Horger, Canton, Ohio, assignor to The Timken Roller Bearing Company, Canton, Ohio, a corporation of Ohio

Application March 15, 1933, Serial No. 660,807

11 Claims. (Cl. 105—79)

My invention relates to railway trucks, particularly to the arrangement of the axle and bearing parts in the side frame members of such trucks. It is extremely difficult to install the usual type of roller bearing axle assemblies in conventional railway truck frames adapted for plain bearings due to the increased size of the roller bearings over the plain ones. This is particularly true in the case of comparatively large integrally cast locomotive truck frames wherein it is impracticable to make the axle openings of the frame large enough to accommodate the usual type of roller bearing axle housing assemblies.

The principal object of this invention is to provide an axle and roller bearing assembly for a railway truck which will be able to withstand the stresses encountered, but which will be narrower in width than the usual type of such assemblies so that it can be installed in a plain bearing truck frame without widening the axle openings thereof. A further object is to provide a construction of this type which is simple in construction and which is readily dismantled for inspection purposes and the like.

The invention consists principally in a railway truck wherein the usual enlarged journal box portions of the housing that enclose the bearings are dispensed with, and wherein the outer bearing members or cups of the bearings are made to cooperate directly with the side frame members of the truck. The invention also consists in removably attaching closure or housing members to the ends of the bearing cups so that they can be readily removed, and in constructing and arranging the bearing parts so that after the closure or housing members have been removed, the bearing parts can be readily moved along the axle into a convenient position for inspection purposes and the like. The invention further consists in the constructions and combinations and arrangements of parts hereinafter described and claimed.

In the accompanying drawings which form part of this specification and wherein like reference numerals refer to like parts wherever they occur,

Fig. 1 is an end view, with the outer end of the axle and wheel cut away, of an axle and bearing assembly embodying my invention and mounted in a side frame member of a railway truck, and it is a view along the line 1—1 in Fig. 2.

Fig. 2 is a central vertical section of the axle and bearing assembly, being a view along the line 2—2 in Fig. 1.

Fig. 3 is a central horizontal section along the line 3—3 in Fig. 2.

Fig. 4 is a vertical section along the line 4—4 in Fig. 2.

Fig. 5 is a vertical section similar to Fig. 2 of 60 a modification of the invention.

Fig. 6 is an end view partially in section of the split outer bearing member or cup used in the modification disclosed in Fig. 5.

Fig. 7 is a side view of the split bearing cup 65 shown in Fig. 6.

Fig. 8 is a vertical section similar to Fig. 2 of another modification of the invention.

Fig. 9 is a horizontal section along the line 9—9 in Fig. 8. 70

Fig. 10 is a vertical section similar to Fig. 2 of another modification of the invention.

Fig. 11 is a horizontal section along the line 11—11 in Fig. 10, and

Fig. 12 is a view looking at the inner end of 75 the assembly shown in Fig. 10 with the axle cut away, being a view along the line 12—12 in Fig. 10.

In the accompanying drawings is shown a part of a conventional integrally cast locomotive truck 80 side frame 1 having an axle opening 2 defined by pedestals whose bottoms are connected by a pedestal tie member 3. The pedestal 4 on one side of the axle opening extends vertically, whereas the pedestal 5 on the other side thereof is inclined to make the opening wider at its bottom. 85 The vertical pedestal 4 has a channel-shaped frame liner 6 fitted around it. The inclined pedestal 5 has a channel-shaped frame liner 7 fitted around it, which has a wedge-shaped web for 90 cooperating with the inclined pedestal. Preferably, a holder block 8 is welded to the pedestal 4 above the top of the frame liner 6 for preventing vertical displacement thereof; and the wedge-shaped liner 7 is provided at its bottom with an 95 adjustment bolt 9 that has threaded engagement with the pedestal tie member 3 for preventing vertical displacement of said liner 7 and for adjusting its position.

In the preferred form of the invention shown 100 in Figs. 1 to 4, inclusive, an axle 10, with a wheel 11 fixed thereon, is disposed within the axle opening 2 in the side frame of the truck. An inner bearing member or cone 12 having two raceway 105 portions, and having its smaller diameter at its middle, is mounted on the axle. The inner end of said cone abuts against the end of an annular rib 13 provided on the axle; the outer end of said cone abuts against the end of a spacer ring 110

14 fixed on the axle between said cone and the wheel 11.

Disposed within the axle opening 2 of the truck side frame and mounted around the cone 5 on the axle is an outer bearing member or cup 15 having two raceway portions that cooperate with those of the cone; and two circular sets of conical rollers 16, in suitable cages 17, are interposed between the cup and cone. The cup has a 10 central rib 18 on its inner periphery at its middle for separating the two raceway portions thereof. The cup also has annular recesses 19 in its inner periphery at its ends for receiving rings 20 whose ends facing the middle of the bearing 15 constitute thrust surfaces for the large ends of the conical rollers.

The bearing cup 15, instead of being made in the usual circular form, has flat sides 21, a flat top 22, and a flat bottom 23, making it generally 20 rectangular in shape. The flat sides 21 of the cup directly engage the flat wear faces of the frame liners; and the usual load transmitting spring saddle members 24 of the truck are seated directly on the flat top 22 of the cup.

25 The axle between the side frames of the truck is enclosed in a substantially U-shaped axle housing 25 that is provided with a top cover plate 26 which is removably secured to the axle housing as by bolts 27 extending through said cover plate 30 and into threaded holes provided for such bolts in the top edge portions of the U-shaped housing. The end of said axle housing adjacent to the inner end of the bearing cup is flared out laterally to form vertically disposed side flange portions 28 and an integral bottom flange portion 29, and the side flange portions are extended upwardly above the top of the U-shaped housing at its end. The cover plate 26 is provided with an upright flange portion 30 at its end which fills 40 the space between the upwardly extended flange portions of the side flanges of the axle housing. This upright flange portion 30 of the cover plate 26 and the lateral end flange portions 28 and 29 of the axle housing are provided with a series of 45 bolt holes for receiving bolts 31 for securing the axle housing and its cover plate to the bearing cup. These bolts extend entirely through the cup from end to end thereof and are also used for securing an outer housing member or closure ring 50 32 to the bearing cup. The outer closure ring is mounted around the spacer ring 14 at the outer end of the bearing cone, and it is made generally rectangular in outline with the corner portions thereof cut away as at 33 for accommodating 55 nuts 34 threaded on the ends of four comparatively large bolts 35 that extend through the side end flange portions of the axle housing and through the bearing cup near its respective corners.

60 Both the closure ring and the upright flange portion of the cover plate are arranged to keep the spring saddle members from sliding off of their seats on the top of the bearing cup. The upright flange portion of the cover plate extends 65 above the top of cup and has flange portions 36 at its sides that extend over the top of the cup to form a pocket for the spring saddle member located on the inside of the side frame. Likewise, the closure ring extends above the top of 70 the cup and has a pair of flange portions 37 that extend over the top of the cup to form a pocket for the spring saddle member located on the outside of the side frame.

The inner end of the closure ring abuts against 75 the thrust ring at the outer end of the bearing

cup for holding said ring in place; and the end of the axle housing and the flange portion of the cover plate are made to abut against the thrust ring at the inner end of the bearing cup for holding said ring in place. Preferably, shims 38 conforming in shape to that of the respective ends of the bearing cup are interposed between its respective ends and the adjacent parts bolted thereto, said shims constituting means for adjusting the bearings.

The lateral side flange portions at the end of the axle housing extend beyond the sides of the bearing cup and are provided with thrust blocks 39 that have flat thrust surfaces facing the inner flanges of the frame liners for engaging the same for preventing excessive endwise movement of the entire axle and bearing assembly with respect to the truck frame. Such flange portions are, preferably, strengthened by integral webs 40 provided at the sides of the axle housing.

9. The construction hereinabove described may be 95 readily dismantled as follows: The truck frame is jacked up and the entire wheel and axle assembly dropped therefrom. The bolts securing the axle housing, the cover plate, and the outer 100 closure ring to the bearing cup are removed. The cover plate is then lifted from the axle housing and the axle housing dropped to the floor. With the cover plate and axle housing out of the way, the inner thrust ring is pulled out of its seat in 105 the cup recess. This removal of the thrust ring allows the inner set of rollers and cage assembly to be pulled out of the cup and inwardly along the axle and thereafter the cup, together with the outer set of rollers and cage assembly 110 so that all of the bearing parts can be brought into a convenient position where they are completely exposed for inspection, or the like.

In the modification illustrated in Fig. 5, the 115 position of the bearings is reversed from that shown in the preferred form. The inner bearing member or cone 12a has its largest diameter at its middle and is provided on its outer periphery at its middle with an annular positioning rib 41 and at its ends with annular thrust ribs 42; and 120 the outer bearing member or cup 15a is split at its center to allow removal of the bearing parts. The two half sections of the composite cup are, 125 obviously, held firmly together by the bolts 31 and 35 which secure the axle housing, the cover plate, and the outer closure ring to the respective ends of the composite cup. Preferably, instead of splitting the bearing cup in a single plane, it is advisable to provide one of the half sections of the bearing cup with an annular 130 flange 43 that projects from its end facing the outer half section of the cup and fits into an annular mating recess 44 provided therefor in the adjoining end of the other half section of the bearing cup. Also in some instances, when the 135 split type of bearing cup is used, it is advisable to further clamp the two half sections of the composite bearing cup together by the arrangement shown in Figs. 6 and 7. In this construction, each side of the composite bearing cups is 140 provided with a central circular groove 45 which is slightly under-cut at its bottom, and a clamping ring 46 whose cross section corresponds to that of the groove is pressed in the groove. The clamping rings 46, when assembled within the 145 circular grooves 45, obviously, prevent the two half sections of the composite cup from spreading apart; and it is impossible for the clamping ring to work loose due to the undercut shape of the grooves.

With this form of the invention, the housing and bearing parts are readily dismantled as follows: The truck is jacked up, and the axle assembly dropped therefrom. The bolts holding the two half sections of the cup and securing the closure and housing members thereto are removed. The cover plate is lifted from the housing; the housing is dropped to the floor; and the wheel is removed. This leaves the axle and bearing parts exposed and by prying the clamping rings loose, the two half sections of the composite bearing cup are free to separate so that the inner bearing parts can be brought inwardly along the axle and the outer bearing parts outwardly along the axle where they can be readily inspected.

In the modification illustrated in Figs. 8 and 9, the general arrangement of parts and the position of the bearings are quite similar to that of the preferred form of the invention, except that the outer bearing member or cup 15b is made plain; and the inner bearing member or cone 12b is provided at its middle on its outer periphery with an integral thrust rib 47 for the small ends 25 of the rollers and at its outer end with an integral thrust rib 48 for the large ends of the outer set of rollers. The cone 12b at its inner end is provided with an angular groove 49 in its outer periphery for receiving a split ring 50 snapped, or 30 otherwise fitted therein, which holds a thrust ring 51 in place that encircles the cone and that is provided with a thrust surface for the large ends of the inner set of rollers. With this arrangement, the parts are readily inspected by 35 removing the axle housing, the cover plate, and the outer closure ring in a manner similar to that for removing the same parts in the preferred form. With these parts removed, the split ring 50 is removed from the groove 49 in which it is 40 seated, which removal allows the thrust ring and the inner roller and cage assembly, followed thereafter by the cup and outer roller and cage assembly, to be moved inwardly along the axle.

In the modification shown in Figs. 10 to 12, 45 inclusive, the construction of the outer closure ring and of the bearing parts is similar in all respects to that of the corresponding parts of the modification illustrated in Figs. 8 and 9 and just described. However, in this form of the invention, instead of using a U-shaped axle housing that extends between the side frames of the truck, a housing member in the form of a comparatively large inner closure ring 52 is bolted to the inner end of the bearing cup 15b in a manner similar 50 to that of bolting the U-shaped axle housing to the cup in the other forms of the invention. This inner closure ring encircles the integral cone engaging thrust rib 13 provided on the axle. Said closure ring 52 extends above the top of the bearing cup and is provided with flange portions 36c extending over the top of the cup to form a 55 pocket for the inner saddle member 24; and the side portions of said closure ring 52 extend beyond the sides of the bearing cup and support the thrust blocks 39 bolted to said side portions for engaging the inner flanges of the frame liners for preventing endwise movement of the axle assembly. The steps required for dismantling this form of construction are, obviously, quite similar to those described in connection with the other forms of the invention; it is believed unnecessary to describe such steps in detail.

With the constructions hereinabove described, by forming the bearing cups so that they cooperate directly with the side members of the truck,

an axle and bearing assembly, conforming to my invention can be made considerably narrower than the usual type of such assemblies that are provided with bearing housings. Accordingly, my axle and roller bearing assembly can be installed in a conventional truck frame adapted for plain bearings at a comparatively low cost. In equipping a conventional plain truck frame with my axle and roller bearing assemblies, the only work required to be done on the pedestal members of the truck frame is to machine such members slightly to straighten them out and to properly align them; and in some cases where the pedestal members are not worn to any great extent, such slight machining operations may even be unnecessary.

As pointed out hereinabove, the axle and roller bearing assemblies embodying my invention are readily dismantled so that the bearing parts thereof can be brought into a convenient position where they are readily accessible for inspection purposes, and the like. Furthermore, it is to be noted that the constructions are extremely simple. They can be made for about the same cost as that of the usual type of roller bearing axle constructions which could only be installed in a plain bearing truck frame by making the axle openings wider which would involve considerable expense and which widening of the openings would have the disadvantage of weakening the frame.

Obviously, the constructions hereinabove described admit of considerable variations without departing from the scope of the invention; accordingly, I do not wish to be limited to the precise constructions and arrangements of parts shown and described.

What I claim is:

1. The combination of a railway truck frame, an axle, roller bearings mounted thereon, said bearings each comprising an outer raceway member formed with its exterior side surfaces substantially vertical for direct cooperation with the side frame members of said truck frame, a housing extending partially around said axle with its ends secured to the inner ends of said raceway members, and a cover removably secured to said housing for completely enclosing said axle, the ends of said cover and said housing being removably secured to the ends of said outer raceway members.

2. The combination of a railway truck frame, an axle, roller bearings mounted thereon, said bearings each comprising an outer raceway member formed with its exterior side surfaces substantially vertical for direct cooperation with the side frame members of said truck frame, a substantially U-shaped housing mounted around said axle with its ends secured to the inner ends of said raceway members, a cover secured to said housing for completely enclosing said axle, a closure ring mounted around said axle at the outer end of said bearings, and means extending through each outer raceway member from end to end thereof for securing the axle housing, the cover therefor, the closure ring and said outer raceway member.

3. The combination of a railway truck frame, an axle, roller bearings mounted thereon, said bearings each comprising an outer raceway member formed with its exterior side surfaces substantially vertical for direct cooperation with the side frame members of said truck frame, said outer raceway member having annular recesses in its inner periphery at its ends, thrust rings 145

for the bearing rollers disposed in said recesses, and housing members mounted around said axle with its ends secured to the inner ends of said raceway members, said housing members abutting against said thrust rings for holding them in place.

4. The combination of a railway truck frame, an axle, roller bearings mounted thereon, said bearings being provided with an outer raceway member formed with its sides substantially vertical for direct cooperation with the side frame members of said truck frame, said outer bearing member having annular recesses in its inner periphery at its ends, thrust rings for the bearing rollers disposed in said recesses, a substantially U-shaped housing mounted around said axle and means for fastening the ends of said housing to the inner ends of said outer raceway members, a cover plate secured to said housing, the ends of said cover plate and said housing abutting against the inner thrust ring to hold it in place, a closure ring mounted around said axle at the outer end of said bearings, said closure ring abutting against said outer thrust ring to hold it in place, said fastening means comprising bolts extending through said outer raceway members, the housing, cover plates and closure rings.

5. The combination of a railway truck frame, an axle, roller bearings mounted thereon, said bearings being provided with an outer bearing member formed for direct cooperation with the side frame members of said truck frame, a housing member mounted around said axle at the end of said bearings, the side portions of said housing extending beyond the sides of said outer bearing member, thrust members provided on the side portions of the housing member for cooperating with the pedestal members of the truck frame, and means extending through said side housing member and into said outer bearing member for securing said housing member thereto.

6. The combination of a railway truck frame, an axle, roller bearings mounted thereon, said bearings being provided with an outer bearing member formed for direct cooperation with the side frame members of said truck frame, a housing mounted around said axle at the end of said bearings, the end of said housing adjacent to the bearings being flanged out laterally to form side flange portions which extend beyond the sides of said outer bearing member, thrust members provided on said side flange portions of the housing for cooperating with the pedestal members of the truck frame, and bolts extending through said side flange portions and into said outer bearing member for securing said housing thereto.

7. The combination of a railway truck frame having spring saddle members, an axle, roller bearings mounted on the end portions of said axle and each having an outer raceway member, and a housing for said axle with its ends rigidly secured to the inner ends of said outer raceway members, the spring saddle members being seated directly on the top of said outer raceway member, the upper end portions of said housing members extending upwardly beyond the tops of said raceway members to help keep said spring saddle members on their seats.

8. The combination of a railway truck frame

having an inner spring saddle member and an outer spring saddle member, an axle, roller bearings including an outer bearing member mounted thereon, the spring saddle members being seated on the top of said outer bearing member, a substantially U-shaped housing mounted around the axle at the inner end of said bearings and secured to said outer bearing member, a cover plate secured to said housing and having a flange portion at its end extending above the top of the outer bearing member and cooperating with the inner spring saddle member for keeping it seated on the top of the outer bearing member, a closure ring mounted around said axle at the outer end of the bearings, and secured to said outer bearing member, the upper portion of said closure ring extending above the top of the outer bearing member and cooperating with the outer spring saddle member for keeping it seated on the top of the outer bearing member.

9. The combination of a railway truck frame, an axle vertically movably mounted therein, roller bearings mounted on said axle and each comprising an outer bearing member with substantially vertical outer sides adapted for vertical sliding in the frame and a substantially horizontal top surface adapted to constitute a seat for a saddle member, a housing rigidly connecting said outer bearing members together, said outer bearing members each having two raceway portions and being split between such raceway portions, and means extending through the housing members and the two half sections of the outer bearing member for holding them all together.

10. The combination of a railway truck frame, an axle vertically movably mounted therein, roller bearings mounted on said axle and each comprising an outer bearing member with substantially vertical outer sides adapted for vertical sliding in the frame and a substantially horizontal top surface adapted to constitute a seat for a saddle member, a housing rigidly connecting said outer bearing members together, said outer bearing members each having two raceway portions and being split between such raceway portions, the half sections of the outer bearing member having semi-circular grooves in their sides that form circular grooves when the two half sections of the outer bearing member are placed together, and rings in said grooves for holding the two half sections of the outer bearing member together.

11. The combination of a railway truck frame having an axle opening, an axle vertically movably mounted in said opening, an inner bearing member mounted on said axle near each end thereof, an outer bearing member mounted around each inner bearing member, rollers interposed between said inner bearing members and said outer bearing members, a thrust ring around each inner bearing member at the end of said rollers, said inner bearing member having an annular groove in its outer periphery near its end, a ring removably mounted in said recess for holding said thrust ring in place, and a housing member mounted around said axle with its ends detachably secured to the inner ends of said outer bearing members.

OSCAR J. HORGAN.
